(57) **CLAIM**

The ornamental design for a lice comb, as shown and described.

DESCRIPTION

FIG. 1 is a perspective view of a lice comb showing our new design including an indentation for ergonomic gripping thereof;

FIG. 2 is a front elevational view showing the ergonomic indentation thereof;

FIG. 3 is a rear elevational view thereof;

FIG. 4 is an edge view thereof, the opposite edge view being a mirror image thereof;

FIG. 5 is a top plan view thereof; and,

FIG. 6 is a bottom plan view thereof.
